[57] CLAIM

The ornamental design of housing for an agricultural tractor, as shown and described.

DESCRIPTION

FIG. 1 is a right side elevational view of housing for an agricultural tractor showing our new design; FIG. 2 is a left side elevational view thereof; FIG. 3 is a top plan view thereof; FIG. 4 is a front elevational view thereof; and FIG. 5 is a rear elevational view thereof.

The tires shown in broken lines in FIGS. 1-5 are shown for illustrative purposes only and form no part of the claimed design.
